1. A device for holding a tool head to its handle, comprising a handle having a head end, a socket formed in the head end, a handle end, and a neck portion extending from the head end to the handle end, the handle end being formed with a shoulder, a rider wedge having a neck portion, a pair of legs, and a shoulder, the neck portion of the rider wedge being located between the shoulders of the handle, the rider wedge being arranged to be driven into the handle end, the legs of the rider wedge being arranged to spread apart as the rider wedge is driven into the handle end, and the shoulder of the rider wedge being arranged to cooperate with the shoulder of the handle to hold the rider wedge in the handle end.

UNITED STATES PATENT OFFICE

EDWARD L. BURD, OF MILTON, AND CHARLES BRADFORD TIBBETTS, OF WALPOLE, MASSACHUSETTS, ASSIGNEES TO UNITED SHOE MACHINERY CORPORATION, OF PATERSON, NEW JERSEY, A CORPORATION OF NEW JERSEY

TOOL SECURING DEVICE

Application filed February 10, 1933. Serial No. 618,409.

This invention relates to means for wedging or locking tools on the ends of their handles, and is illustrated as embodied in a shoe hammer.

5 In securing a tool head to its handle it is customary to make use of some form of wedging means driven into the end of the handle in such a way as to spread that part of the handle positioned in the tool head socket, thereby increasing the frictional engagement between the handle and the walls of the 10 socket and consequently lessening the tendency of the tool head to separate from the handle during use of the tool. It frequently happens that the wedging means employed 15 works loose due to the blows to which the tool is subjected or to the shrinkage of the wood in the handle, thus releasing the pressure of the handle against the walls of the 20 socket to such extent that the tool is no longer held upon the handle.

In view of the foregoing, the invention 25 contemplates the provision of improved means for locking the wedging means in operative position. To this end the invention 30 provides a ridden wedge and a rider wedge for securing a tool head on a handle, the rider wedge having legs of substantial width connected by a narrow neck portion straddling the ridden wedge and extending at right angles thereto for cooperating with the 35 ridden wedge to produce a quartering action upon the handle, the arrangement being such that as the rider wedge is driven into the handle the ridden wedge spreads apart the legs of the rider wedge, thus locking both wedges in the handle.

The rider wedge which we prefer to use 40 is of a form which secures many of the advantages of the invention even if it is used alone. As shown in the drawings, this wedge is formed with a narrow neck portion located between sloping shoulders and opposite the neck portion the wedge is formed with rigid 45 legs having diverging inner edges and substantially straight outer edges. Thus, a hammer blow directed to the narrow neck portion tends to spread the rigid leg members apart and when the wedge is driven into 50 the handle this feature of construction co-

operates with the contour of the inner edges of the leg members in causing a wedging action at right angles to the main wedging action and securely locks the wedge within the hammer handle.

55 The secure locking of the rider wedge locks also the ridden wedge which it straddles, and prevents the slightest loosening. The use of the two wedges, and to a considerable extent the use of the rider wedge alone, spreads the 60 end of the hammer handle in two directions, substantially quartering it, and tightly wedges it against all sides of the socket in the tool head.

65 The above and other features of the invention, including a novel construction permitting the use of relatively-inexpensive cast metal for the rider wedge, or for other forms of spreading wedges, will be apparent from the following description of one form of the 70 invention shown in the accompanying drawings, in which:

75 Figure 1 is a perspective view showing part of a shoe hammer, and the wedges before they are inserted;

Fig. 2 is a perspective view showing the 75 wedges partly inserted;

Fig. 3 is a perspective view showing the 80 wedges completely inserted; and

Fig. 4 is a side elevational view in section 85 showing the wedges inserted within the tool handle.

The tool shown in the drawings comprises a head 10, formed with the usual socket in which is inserted one end of a handle 12. 85 The ridden wedge 14, which is inserted first, is formed with an inner wedge portion 16, extending substantially across the end of the handle 12, and an outer wedge portion 18. To protect the outer wedge portion when the 90 wedge 14 is driven into the end of handle 12, driving portions 20 are provided, one on each side of wedge portion 18.

The rider wedge 30 is formed with a pair 95 of depending legs 32 arranged to straddle and be spread apart by the outer wedge portion 18 of the ridden wedge. These legs are formed with substantially straight outer edges, and with diverging inner edges 34 to be spread apart by the wood of the hammer 100

handle. As shown clearly in Fig. 1 the legs 32 are connected by a narrow neck 35 at the outer extremity of the wedge and the inner edges of the legs approach each other closely at a point spaced somewhat below the neck 35 defining the opening 36. The width of the neck 35 is made substantially less than the average width of the legs 32 between their inner and outer edges so that the material of the neck will yield or break as may be necessary to permit the legs to spread apart as the wedge 30 is driven into place. Below the opening 36 the inner edges of the legs diverge gradually to the pointed lower ends of the legs. The formation and relative arrangement of the neck 35 and the opening 36, and the gradual divergence of the inner edges of the legs particularly adapt the legs to be spread apart as the wedge is being driven into place in the handle. Furthermore, the neck 35 being located at the outer extremity of the wedge is adapted to receive a blow from a hammer or other implement used for inserting the wedge and the blow will be received at such a point relatively to the rest of the wedge that it will have a tendency to spread apart the legs of the wedge and to lock them in place.

While for convenience of illustration both 30 wedges are shown partly inserted in Figure 2, it is to be understood that the ridden wedge may be completely inserted first, and then the rider wedge driven home to assume the position shown in Fig. 4. The rider and 35 ridden wedges are of substantially equal lengths and are so shaped that they are adapted to be driven into the tool handle to equal depths exerting a quartering action throughout their lengths.

40 It is to be noted that it is not important if a fin connects the legs 32 below hole 36, as it will be split by wedge portion 18. Moreover, since the locking action of one leg 32 is entirely independent of that of the other, it is not important if the rider wedge 30 splits entirely in two as it is finally seated. For these reasons the wedges may be made 45 of iron or other metal by casting, and are much less expensive than previous spreading wedges, in which high elasticity is essential, necessitating their manufacture by more expensive methods, usually from steel. No machining or other finishing is necessary, the wedges being ready for use as cast.

55 While the invention has been described as embodied in a shoe hammer, it is not our intention to limit its scope thereby, or otherwise than by the terms of the appended claims.

60 We claim—

1. A spreading wedge of substantial width to exert a splitting action on the part into which it is inserted, the wedge being bifurcated to provide two depending legs connected by a narrow neck and having inner

edges which approach each other closely at a point beyond the neck and diverge gradually from said point to form points at the free extremities of the legs.

2. A device for securing a tool head on a handle comprising a ridden wedge, and a rider wedge having legs of substantial width connected by a narrow neck portion and extending at right angles to the ridden wedge, the wedges co-operating to exert a quartering action on the handle throughout their entire lengths, the ridden wedge being provided with means operable when the rider wedge is driven into the handle to spread apart the legs of the rider wedge thus locking both 80 wedges in the handle.

In testimony whereof we have signed our names to this specification.

EDWARD L. HURD.
